UNITED STATES PATENT OFFICE.

JOHN TOTH, OF STEINWAY, LONG ISLAND CITY, NEW YORK.

DOOR-LOCK.

No. 800,417.

Specification of Letters Patent.

Patented Sept. 26, 1905.

Application filed September 21, 1904. Serial No. 225,302.

To all whom it may concern:

Be it known that I, JOHN TOTH, a citizen of the United States, residing at Steinway, Long Island City, in the county of Queens and State 5 of New York, have invented certain new and useful Improvements in Door-Locks, of which the following is a specification, such as will enable those skilled in the art to which it app pertains to make and use the same.

10 This invention relates to locks for doors; and the object thereof is to provide an improved device of this class involving an ordinary latch-bolt and two lock-bolts adapted to be operated by a single key, the construction of the 15 lock being such that the lock-bolts cannot be operated even by one having the proper key, unless he be familiar with the construction and operation of the lock.

The invention is fully disclosed in the following specification, of which the accompanying drawings form a part, in which the separate parts of my improvement are designated by suitable reference characters in each of the views, and in which—

25 Figure 1 is a front view of the lock with the front of the casing removed and showing part of the construction broken away and showing also the key inserted; Fig. 2, a similar view showing the parts in a different position; Fig. 30 3, a similar view showing the parts in another position; Fig. 4, a section on the line 4-4 of Fig. 1, and Fig. 5 a section on the line 5-5 of Fig. 2.

In the practice of my invention I provide a 35 lock-case *a*, which is rectangular in form and provided with a face-plate *a*², which is designed in practice to be countersunk in and secured to the face of the door, and at *a*³ I have shown a similar plate designed to be countersunk in and secured to the door-frame adjacent to the lock.

In the top portion of the lock-case *a* is a 45 latch-bolt *b*, provided with the usual beveled head *b*² and which is normally held in a horizontal position, as shown in Fig. 1, and the 50 knob-spindle *b*³ passes through the case *a* below the inner end of the bolt *b* and is provided with a hub *b*⁴, the side of which adjacent to the face-plate *a*² of the case is provided with an upwardly-directed finger *b*⁵ and a downwardly-directed finger *b*⁶, and pivoted below and slightly to the right of the spindle *b*³, as shown at *b*⁷, is an upwardly-directed dog *c*, the upper end of which is provided with a forwardly-directed 55 nose *c*², in connection with which the finger *b*⁵

operates, and the inner end of the bolt *b* is pivoted to the dog *c* at *c*³ and secured to the case *a* at the right of the dog *c*, and below the spindle *b*³, as shown at *c*⁴, is a spring *c*⁵, which operates on the pivot-pin at *c*³ and normally forces the bolt *b* into operative position, as shown in Fig. 1, and the bolt *b* or the head *b*² thereof may be withdrawn by turning the knob-spindle *b*³ in either direction. When the knob-spindle *b*³ is turned in one direction, the finger *b*⁵ of the hub *b*⁴ strikes the nose *c*² of the dog *c* and forces the upper end of said dog backwardly, and this withdraws the bolt *b* and the head *b*² thereof, and when the knob-spindle *b*³ is turned in the other direction the finger *b*⁶ of the hub *b*⁴ presses on a forwardly-directed projection *c*⁶ of the dog *c*, and this also forces the upper end of said dog backwardly and withdraws the latch-bolt *b* and the head *b*² thereof.

In the bottom portion of the case *a* and parallel with the latch-bolt *b* are two lock-bolts *d* and *e*, provided, respectively, with heads *d*² and *e*², which are adapted to be projected through the face-plate *a*², and said bolts *d* and *e* are provided, respectively, with a transverse shoulder *d*³ and *e*³, and springs *d*⁴ and *e*⁴ are secured in the case *a*, as shown at *x*, and bear on said shoulders, so as to normally project the bolts *d* and *e* or the heads *d*² and *e*² thereof. The bolts *d*² and *e*² are thinner than the heads thereof, and said bolts are provided centrally thereof with longitudinal slots *d*⁵ and *e*⁵, respectively, and the adjacent edges of said bolts are cut out longitudinally, 90 as shown at *d*⁶ and *e*⁶, so that the said bolts are narrower in vertical section than the heads *d*² and *e*² thereof.

The upper edge of the bolt *d* is provided with two notches or recesses *d*⁷ and *d*⁸ and the lower edge of the bolt *e* with similar notches or recesses *e*⁷ and *e*⁸, and said bolts are provided at their inner ends with a longitudinal slot *d*⁹ and *e*⁹, respectively, and secured to back of the case *a* are pins *x*², which project through the slots *d*⁹ and *e*⁹ and form guides for the rear ends of said bolts.

Placed on the bolt *d* is a plate *f*, the upper edge of which is provided with an arm *f*², which projects in the direction of the plate *a*² and is pivoted in the case *a* adjacent to said plate, as shown at *f*³; and the arm *f*² and the plate *f* adjacent thereto is provided with a backwardly-directed flange *f*⁴, adapted to rest on the top edge of the bolt *d* and at the 110

right-hand end of which is a downwardly-directed tooth f^5 , adapted to engage the notches or recesses d^7 and d^8 in said bolt, and secured in the case a above the arm f^2 is a 5 spring f^6 , which bears on the inner end of the flange f^4 and normally forces the plate f downwardly into the position shown in Fig. 1, and in Figs. 2 and 3 the plate f is broken away, so as to show the flange f^4 and the operative parts in connection therewith.

Placed on the bolt d and between said bolt and the plate f is a dog g , which is pivoted in position by means of a pin g^2 , passing through the slot d^5 and secured to the case 15 a , and the upper end or head of the dog g is oblong and rectangular in form and provided with a longitudinal groove or recess g^3 , and said dog g is provided with a nose g^4 , which projects downwardly to the right.

Pivoted to the inner lower corner of the bolt d , as shown at g^5 , is a dog h , which extends in the direction of the face-plate a^2 and the end of which is provided with a downwardly-directed nose h^2 , an upwardly-directed 20 nose h^3 , and a forwardly-directed nose h^4 . The upper side of the dog h is cut out to form a recess h^5 , and placed between the bolt d and the plate f is a spring i , having two arms, one of which passes through the slot g^6 in the 25 head of the dog g and bears on the flange f^4 of the plate f , and the other arm of which is firmly held in the nose h^3 of the dog h , and said spring is provided with a coil i^2 , which rests in the recess h^6 in the top of said dog, 30 and the spring i is weaker than the spring f^6 , so that in the normal position of these parts the plate f will be held in the position shown in Fig. 1.

A plate j is placed on the bolt e and is similar in all respects to the plate f , except that the upper edges thereof are cut out to form a recess j^3 . The plate j is provided with an arm j^2 , pivoted at j^5 , and said arm and plate are provided with a backwardly-directed 40 flange j^4 , which bears on the bottom of the bolt e , and the inner end of which is provided with an upwardly-directed tooth j^5 , which is adapted to enter the notches or recesses e^7 and e^8 in the bottom edge of the bolt e , and a 45 spring j^6 is placed below and bears on the backwardly-directed flange j^4 of the plate j and normally holds said plate in the position shown in dotted lines in Figs. 1 and 2 and shown partially in dotted and partially in full 50 lines in Fig. 1. A dog k , similar to the dog g , is placed between the bolt e and the plate j and is pivoted on a pin k^2 , passing through the slot e^5 in the bolt e , and is provided at its lower end with an oblong rectangular head 55 k^3 and at its upper end with a nose k^4 , which projects upwardly and to the right. It will be observed that the dog k is similar to the dog g , but the position thereof is reversed, and pivoted to the inner end and upper corner 60 of the bolt e , as shown at k^5 , is a dog m ,

which projects to the left and the end of which is provided with an upwardly-directed nose m^2 , a downwardly-directed nose m^3 , and a forwardly-directed nose m^4 , and the bottom portion of said dog is cut out to form a recess m^5 . Placed between the bolt e and the plate j is a 70 spring n , formed into a coil n^2 , which fits in the recess m^5 in the dog m , and one arm of said spring projects toward the face-plate a^2 and passes through a groove or recess in the head k^3 of the dog k , and the other arm thereof is short and secured in the nose m^3 of the dog m .

It will be observed that the dog m , the spring n , the dog k , and the spring j^6 , together 80 with the plate j , are similar to the corresponding parts h , i , g , f^6 , and f , hereinbefore described and operating in connection with the bolt d ; but the position of the parts which operate in connection with the bolt e are reversed.

In the operation of the latch-bolt when the knob-spindle b^3 is turned in either direction the corresponding finger b^5 or b^6 operates to force the head b^2 of the latch-bolt b out of engagement with the plate a^2 of the door-frame, and upon the releasing of the spindle b^3 the spring c^5 forces said head b^2 outwardly into engagement with said plate a^2 . In operating the lock-bolts, reference being made to Fig. 1 of the drawings, in which the bolts d and e are drawn backwardly out of engagement with the plate a^2 , it will be seen that when the key o is revolved from its initial entrance position in either direction said key or the lug thereof will engage the noses m^2 or h^4 of the dogs m or h , according to the direction in which said key is turned, and if the key strikes the nose m^2 the dog m is depressed and the spring n connected thereto and normally bearing 105 upon the tooth j^5 of the plate j said tooth will be forced out of the recess j^5 , and the bolt e being thereby released is forced outwardly into the position shown in Fig. 2 by means of the spring c^4 , and the door is locked 110 thereby by means of the head e^2 of said bolt. Upon continuing the rotation of the key o the lug thereof strikes the nose g^4 of the dog g or in the other direction the nose h^2 of the dog h , and the same result follows as described with reference to the bolt e , and the bolt d is shot outwardly by means of the spring d^4 , and the door is locked by both of the bolts d and e at this time, and if the key 115 strikes the noses g^4 and h^4 of the dogs g and h , respectively, said dogs being mounted upon fixed pivots, the corners of the heads of the dogs g and h adjacent to the flange j^4 of the plate j or the flange f^4 of the plate f will force said corresponding flange and plate outwardly, as clearly shown in dotted lines in Fig. 1 and full lines in Fig. 3, and it will therefore be seen that after the key is inserted into the lock and slightly rotated in either direction the bolt e is released and 120

125 either direction the bolt e is released and 130

forced outwardly and upon continued rotation of the key the bolt *d* is released and forced outwardly and the door is locked.

In Fig. 3 of the drawings both the bolts 5 are shown in their outward position and the key *o* is shown after having described an arc of ninety degrees, at which time it has come in contact with the nose *h*⁴ of the dog *k* and forced the plate *j* outwardly, thus releasing the 10 tooth *j*⁵ thereof from the recess *e*⁸, in which at this time it normally rests, and upon a slightly greater arc being described by the key the 15 said nose *h*⁴ of the dog *k* is released and the tooth *j*⁵ again enters the recess *e*⁸ because of the spring *j*⁶ and the bolt *e* has not been forced backwardly, and if the key *o* is still further revolved the lug thereof strikes the 20 nose *g*⁴ of the dog *g* and forces said dog into the position shown in Fig. 3, and the nose *g*⁴ thereof coming in contact with the nose *h*² of the dog *h* said dog is forced upwardly, and although at this time the tooth *f*⁵ of the flange *f*⁴ of the plate *f* is disengaged from the recess *d*⁸, in which it rests, the key *o*, having 25 no projection upon the bolt *d* or dogs *g* or *h* to engage with, said key continues its rotation until the said dogs are released and forced into their normal position by means of the spring *i*, and the plate *f* resuming its normal 30 position the tooth *f*⁵ of the plate *f* again enters the recess *d*⁸ and the door remains locked, and if from the position shown in dotted lines at *p* in Fig. 3 the key is turned to the left it strikes the nose *h*⁴ of the dog *k*, which in turn 35 strikes the nose *m*² of the dog *m* and the result described with reference to the dogs *g* and *h* follows, said dog *m* being depressed, and the tooth *j*⁵ of the plate *j* is released from the recess *e*⁸ of the bolt *e* and the key striking 40 no projection with which it can engage continues its rotation beyond the dogs *h* and *m*, which resume their normal positions because of the spring *n* when said key has passed and the bolt *e* has not therefore been withdrawn 45 and the door remains locked.

It will therefore be seen from the foregoing description that a person not knowing the operation of my lock will be unable to withdraw either of the bolts *d* or *e* and cannot 50 therefore unlock the door; but if it is desired to withdraw the bolts *d* and *e* the key *o* is rotated in the direction of the arrow *y*² in Fig. 2 through an arc slightly greater than one hundred and eighty degrees or until it passes 55 the nose *h*² of the dog *h* and the dog *h* has resumed its normal position, and if at this time the key *o* be revolved in the direction opposite the arrow *y*² the lug of the key *o* is engaged in the recess between the noses *h*⁴ 60 and *h*² of the dog *h*, and the continued rotation of the key in this direction forces the bolt *d* backwardly out of engagement with the plate *a*³ and when so forced to its extreme backward position and the lug of the key *o* having come 65 into contact with the plate *f* in its rotation

and the tooth *f*⁵ thereof being therefore released from the recess *d*⁸ in the bolt *d* when the key *o* has so forced the bolt *d* backwardly to its extreme position and has released the plate *f* the tooth *f*⁵ thereof then bears against 70 the upper side of the bolt *d*, and when the said bolt *d* is at its extreme backward position the tooth *f*⁵ of the plate *f* enters the recess *d*⁷ in said bolt and the bolt *d* and head *d*² thereof are out of engagement with the plate *a*³ and 75 the door is therefore unlocked as regards the bolt *d*.

If the key *o* is rotated in the direction opposite the arrow *y*² until it passes the nose *m*² of the dog *m* in the position shown in Fig. 2, 80 the lug of said key has depressed the plate *j* by coming in contact therewith, and the tooth *j*⁵ thereof is therefore out of engagement with the recess *e*⁸, and if the key is at this time revolved in the direction of the arrow *y*² the 85 lug of said key bearing against the nose *m*² of the dog *m* forces the bolt *a* backwardly until the lug of said key releases the plate *j*, which is then forced into its normal position by means of the spring *j*⁶, and when the bolt *e* 90 has been so forced to its extreme backward position the tooth *j*⁵ of the plate *j* enters the recess *e*⁷, and the bolt *e* is therefore withdrawn and the head *e*² thereof is out of engagement with the plate *a*³ and the door is unlocked. 95

It will be understood, of course, that the key is rotated no farther than is necessary to pass the nose *h*² of the dog *h* or *m*² of the dog *m*, for if still farther rotated it would pass the noses *g*⁴ or *h*⁴ of the dogs *g* or *h*, respectively, and continued rotation would repeat the operation described and shown with reference to the dogs *g* and *h* in Fig. 3, and the door would not be unlocked, and very little practice is necessary to accustom a person as 100 to the degree of rotation of the key *o* in either direction to withdraw the bolt *d* or *e*; but without the knowledge necessary as to the degree of rotation said door cannot be opened. 105

Having fully described my invention, what 110 I claim as new, and desire to secure by Letters Patent, is—

1. A lock, comprising a casing provided with two lock-bolts one of which is placed above the other, springs for projecting said bolts, a plate pivoted in said casing so as to swing in a plane parallel with and adjacent to the upper bolt, said plate being adapted to engage said bolt and hold it in a withdrawn position, a spring for depressing said plate, a 115 dog pivoted between said plate and said bolt by a pin passing through a slot in said bolt, another dog pivoted to the inner end of said bolt, a spring in operative connection with the last-named dog and adapted to raise said plate, a plate pivoted adjacent to the bottom bolt and adapted to swing in a vertical plane parallel with and adjacent thereto and to engage said bolt and hold it in a withdrawn position, a spring for raising said plate, a dog 120

125 130

pivoted between said plate and said bolt, another dog pivoted to the inner end of said bolt, a spring in operative connection with the last-named dog and adapted to depress said plate, and means whereby the said dogs may be operated by a single key and either or both of said bolts projected, substantially as shown and described.

2. A lock comprising a casing provided with two spring-projected lock-bolts placed one above another and in the same vertical plane, a plate pivoted so as to swing in a vertical plane parallel with and adjacent to the top bolt, said plate being adapted to engage said bolt and hold it in a withdrawn position, means for holding said plate in a depressed position, a dog pivoted between said plate and said bolt, another dog pivoted to the inner end of said bolt, means for depressing the last-named dog and raising said plate, a plate pivoted adjacent

to the bottom bolt and adapted to swing in a vertical plane parallel therewith and adjacent thereto and adapted to hold said bolt in a withdrawn position, means for raising said plate, a dog pivoted between said plate and said bolt, another dog pivoted to the inner end of said bolt, means connected with the last-named dog for raising said plate, and means whereby said dogs may be operated by a single key and either or both of said bolts projected, substantially as shown and described. 25 30

In testimony that I claim the foregoing as my invention I have signed my name, in presence of the subscribing witnesses, this 19th day of September, 1904.

JOHN TOTH.
